(57) **CLAIM**

The ornamental design for a drinking cup lid and removable headband combination, as shown and described.

DESCRIPTION

FIG. 1 is a perspective view of the drinking cup lid and removable headband combination in accordance with the present invention shown in a position of use on an unclaimed cup;

FIG. 2 is a front elevational view thereof;

FIG. 3 is a rear elevational view thereof;

FIG. 4 is a top plan view thereof;

FIG. 5 is a right side view thereof, the left side view being a mirror image; and,

FIG. 6 is a bottom plan view thereof.

The broken lines depicting a cup in FIG. 1 illustrate environmental subject matter that forms no part of the claimed design. The circular broken line inside of the perimeter of the bottom plan view in FIG. 6 represents an inner boundary to the claim and forms no part thereof. All other broken lines

(Continued)

depict portions of the drinking cup lid and removable headband combination that form no part of the claimed design.
